AUTOMATIC FACET FORMING MACHINE

Aaron Simons, Bronx, N. Y.

Application June 3, 1942, Serial No. 445,630

26 Claims. (Cl. 51—229)

This invention relates to machines for automatically producing a predetermined number of facets on diamonds or other precious stones and the object of the invention is to provide a machine of this class employing a tool supporting head, with means actuated upon the completion of a predetermined operation on a stone for automatically shifting the head to bring another section or area of the stone in position to be formed or shaped, further in automatically repeating this operation until all of the facets have been completely formed on the stone, and in providing means for adjusting angularity of the tool, as well as to automatically shift the position of the tool in intermittently changing position of the workpiece or stone with respect to the grinding or shaping element; and with these and other objects in view, the invention consists in a machine of the class and for the purpose specified, which is simple in construction, efficient in use, and which is constructed as hereinafter described and claimed.

The invention is fully disclosed in the following specification, of which the accompanying drawings form a part, in which the separate parts of my improvement are designated by suitable reference characters in each of the views, and in which:

Fig. 1 is a side and sectional view of a machine made according to my invention showing the tool supporting head in operative position.

Fig. 2 is a side view of the machine showing the tool supporting head in raised inoperative position.

Fig. 3 is a plan view of the machine, as seen in Fig. 1.

Fig. 4 is a view similar to Fig. 3 showing parts in a different position and omitting part of the construction.

Fig. 5 is a view looking in the direction of the arrow 5 of Fig. 1 showing only a part of the construction and with parts in section.

Fig. 6 is a partial section on the line 6—6 of Fig. 1.

Fig. 7 is a partial section on the line 7—7 of Fig. 3.

Fig. 8 is an enlarged sectional view on the line 8—8 of Fig. 5.

Fig. 9 is a perspective view diagrammatically showing a swinging frame control mechanism of the machine.

Fig. 10 is a face view of a diamond indicating the facets formed thereon.

Fig. 11 is a section on the line 11—11 of Fig. 2 on an enlarged scale.

Fig. 12 is a section on the broken line 12—12 of Fig. 1 omitting parts of the construction, and

Fig. 13 is a partial section on the line 13—13 of Fig. 4.

In the drawings, 15 represents a base or table

of the machine, at one end of which is a raised platform 16 supporting a motor 17 operating a shaft 18 through a belt or other drive 19. On the shaft 18 is a worm 20 driving a worm wheel 5 21 on a transverse cam shaft 22, having two heart shaped cams 23 at opposite ends thereof, which operate upon rollers 24 supported on a sliding frame 25, which operates in suitable guides 26 on the table 15. At the forward end of the frame 10 is a supplemental table 27 forming part of the frame thereon, on which is supported upwardly and forwardly directed side-plates 28 and rearwardly extending bearings 29, the latter forming supports for a pivot 30. The pivot forms an axis for a swinging frame 31.

The swinging frame comprises a cross plate 32 having raised and forwardly directed arms 33, and to the plate 32 is secured a rearwardly directed platform 34 having a cross-bar 35, the 20 terminal ends of which form the pivots 30.

To the forward end of the platform 34 is secured an arc shaped segment 36 having a dovetail channel to slidably receive a sector 37. The sector 37 has upwardly and forwardly extending curved arms 38, which provides an adjustable support for a block 39 in which a workpiece supporting tool 40 is mounted. The block 39 is recessed at one side, as seen at 41, to receive one of the arms 38; the other arm snugly engages the other side of the block. A large milled screw 42 engages the arm in the recess to clamp the block in different positions of adjustment on the arms, in controlling the angular position of the tool with respect to the surface of the grinding wheel 43, which is partially indicated in Figs. 1 and 2 of the drawings. At the forward end of the arms 38 is a cross-head 44 having an upwardly extending pin 45, on which is disposed a weight 46, which acts as a counterbalance to control movement of the swinging frame toward the grinding wheel 43.

At this time, it will be pointed out that the grinding wheel is preferably supported and operated by means totally independent of the machine and the machine is thus adjustably supported as a unit with respect to the grinding wheel and when properly adjusted the block 39 including the tool 40 are adjusted to bring the workpiece or diamond 47 supported in the tool 40 in proper relationship with respect to the surface of the grinding wheel to provide for the automatic grinding of the several facets 48 on the diamond, as is indicated diagrammatically in Fig. 10 of the drawings.

55 In Fig. 11 of the drawings, a section is shown through the block 38 to illustrate generally the workpiece supporting tool mounting. The tool 40 is quickly attachable and detachable with the block by a hooked end arm 49, pivoted as seen 60 at 50 with the hooked end of the arm engaging

an opposed, recessed pin 51, the arm carrying a set screw 52 centrally thereof, which bears upon the outer end of a milled head 53 of a tool retaining sleeve 54. The lower end of this sleeve is internally threaded to engage a chuck sleeve 55, the inner threaded end of which has a key slot 56 engaged by a pin 57 in an outer shell 58 of the tool 40. This keys the chuck sleeve against rotation in the tool holder, while the slit and beveled end 59 of the sleeve is drawn inwardly into engagement with the beveled wall on the shell 58 by the sleeve 54. This operation clamps and firmly grips the workpiece or diamond supporting element or plug 60 firmly in position in the manner indicated in Fig. 11 of the drawings. The plug 60 constitutes more or less of a conventional mounting for the stones.

Secured at the upper end of the outer shell 58 of the tool is a hooked arm 61 which engages the pivot pin 58 to retain the tool against rotation in the inner bushing 62, around which is arranged an outer bushing 63, the latter being supported in the block 39. These two bushings are provided to care for intermittent rotary movement, which is imparted to the tool 40 in bringing successive sections of the workpiece or diamond 47 in position to form the successive facets 48 thereon.

For the time being, the structure of the tool operating mechanism will be described and the means for actuating said mechanism will be later described. Arranged upon the upper end of the block 37 and rotatable on the bushing 63 is a beveled ring 64 to which is secured a ratchet wheel 65. Rotatable upon the upper and lower surfaces of the wheel 65 are spaced discs 66, one extended arm of which carries a swiveled pin 67 and in oppositely extended arms of which is pivotally supported a spring actuated pawl 68. This structure may be said to constitute a pawl actuating frame, which is independently rotatable on the recessed sides of the ratchet wheel 65, as will clearly appear upon a consideration of Fig. 11 of the drawings. This frame is rotated in one direction as later described, to move the pawl over the ratchet wheel while the latter is stationary and is movable with the ratchet wheel in driving or rotating the wheel when the frame is operated in the opposite direction. On the lower surface of the ratchet wheel 65 are eight conical sockets 69 and supported in the block 39 is a spring operated key pin 70, note Fig. 13, adapted to enter one of these sockets to retain the ratchet against rotation in the first described swinging movement or rotation of the pawl frame; whereas in the other movement of the frame, to rotate the ratchet, the rounded end of the pin 70 facilitates forcible depression of this key pin and the same again enters the next successive socket 69 preparatory to the next freeing movement of the pawl frame with respect to said ratchet wheel. In other words, the pin 70 retains the tool in the eight different positions required to form the eight facets on the diamond or workpiece. Where the number of facets are varied, the tool structure and means controlling operation thereof will be correspondingly varied.

From the foregoing, it will be apparent that in the rotation of the ratchet, the disc 64, as well as the tool unit 40, is correspondingly rotated. The bevel disc 64 may have suitable marks or indentures to register with corresponding markings on the upper surface of a stationary disc 71, secured to the block 39 to indicate to the opera-

tor the position assumed by the stone or workpiece during any particular operation.

The lower end portion of the shell 58 protrudes beyond the block 39 and is tapered to seat snugly in a bushed collar 72 having a flange portion 73 to receive screws or other fastenings to mount the same on the lower surface of the block. Removal of this bushed sleeve will facilitate detachment of the tool unit 40, although the unit may be detached without removal of said sleeve. In addition to the rotary movement of the tool unit 40, the entire tool operating mechanism is rotatable in the block 39 by mechanism later described, which rotation is upon the bushing 62.

In the operation of the machine, the reciprocating frame moves back and forth in the machine by the action of the cams 28 and the spring 14, which is coupled with one pin 75 on the plate 27 and another pin 76 on the bedplate 15. In this operation, the workpiece is moved radially over the surface of the grinding wheel 43 or inwardly and outwardly with respect to the axis of rotation of this wheel in any desired angular relationship. After the grinding operation has been performed, said mechanisms, later described, automatically throws the swinging frame into raised position and in so doing, two operations are performed with regard to the workpiece supporting mechanism. First, the complete block is swung into a different angular position by movement of the sector 37 in the guides. In other words, in moving the unit from the position shown in Fig. 3 to that illustrated in Fig. 4 or vice versa, and during this operation the workpiece supporting tool 40 is rotated $\frac{1}{8}$ of a revolution to bring the next section of the diamond or workpiece in position to be ground. The reason for shifting the angular position of the entire unit is to bring the workpiece, if it has a grain, into proper relationship with the grinding wheel to produce the most efficient grinding operations thereon consistent with the graining of the workpiece. This produces the most efficient operations and more highly polished and finished surfaces on the resulting facets.

The first of the above mentioned operations is performed by a swinging arm 77, pivoted as seen at 78, and having at its free end a fork 50 engaging a pin 79 on the sector 37. At the pivot end of the arm 77 is a cross-head 80 having forked ends engaging pins on sliding parallel bars 81 which are supported upon the plate extension 34. At the forward ends of each of these bars are pivoted pawls 82, note Fig. 7, having flat position of the springs and pawls, in other words, when the bars are in retracted positions, the pawls 82 having their ends protruding above the surface of the bars; whereas 60 in extended position, the springs actuate to depress the forward ends of the pawls to provide the following operations.

Pivotedly supported on stationary posts 85, secured to the plate 27, are gravity operated fingers 86 which are of sufficient width to slide freely over the upper surfaces of the bars 81. In the event that the frame is swung on the pivot 38, the one finger 86 will engage the protruding pawl, for example, the pawl shown in full lines in Fig. 7 of the drawings, thus advancing the bar 81 coupled therewith; where the movement of the other finger over the bar will pass freely over the depressed pawl therein. In this operation, the engaged pawl will operate the arm 77 and the sector 75 37 to move the entire unit into a different angu-

lar position. For example, considering Fig. 3, the above described operation would cause the arm 11 to move from the position of said figure to the position shown in Fig. 4. In the next swinging movement of the frame, the arm 11 will be moved from the position shown in Fig. 4 to the position shown in Fig. 3. With the workpiece supporting unit in the position shown in Fig. 4, the diamond or workpiece 47 may be moved radially across the surface of the grinding wheel 43; whereas when in the position shown in Fig. 3, this movement of the diamond or workpiece will be of an angle of approximately 45° to the first mentioned movement.

The aforesaid swinging movement of the frame 31 is accomplished by the movement of a roller 87 over a cam surface 88 in the forward end of the block 16. The roller 87 is supported in one end of the cross-head of a T-shaped arm 87', the other end of which is pivoted, as seen at 89, and the leg of this arm 87' supports an adjustable pin 90 which engages the block 91 on one end of a plunger rod 92. A short guide and key rod 93 is also secured to the block 91 and both rods reciprocate back and forth in the frame in suitable guides or bearings, as clearly seen in Fig. 1 of the drawings.

Secured to the rod 92 is a spring seat and pawl actuating plate 94, note Fig. 9, of the drawings, which has depending side fingers 95 adapted to cooperate with a lip 96 on a pawl 97. Also secured to the plunger rod 92 is a pawl block 98 having a pawl receiving recess 99 in the lower forward corner thereof, which is engaged by the pawl when the frame is automatically swung into raised position. A spring 100, note Fig. 1, normally tends to support the pawl in raised operative position; whereas a spring 101 on the rod 92 supports the block 91 in constant engagement with the pin 90. In the normal reciprocating back and forth movement of the machine in the guides 28, the roller 87 rides over the cam surface 88 and the pin 90 moves the plunger 92 forwardly against the tension of the spring 101 and in this operation, assuming that the grinding operation on the stone or workpiece has not been completed, a spring finger 102 pivoted as seen at 103 engages the lip 96 of the pawl 97 to lower the nose of the cam out of engagement with the block 98, the finger 102 being normally supported in engagement with the lip by a spring 104, note Fig. 1. On the pivot end of the finger 102 is a projecting lip 105 adapted to be engaged by a substantially L-shaped trip plate 106, the angular end 107 of which engages the lip 105. The upper ends of the plate 106 has side wings forming pivotal supports 108 for said plate. The plate is also apertured to freely receive the plunger rod 92. At the upper edge of the plate 106 is a bevelled surface 109 adapted to be engaged by the hook end 110 of a control plate 111. The plate 111 has side pivots 112 for mounting on the segment 38 and at the forward end of the plate 111 is an adjustable stop screw 113 adapted to engage a stop element 114 on the lower surface of a front stop plate 115, the latter having two adjustable stop pins 116, note Fig. 5, which form safety stops limiting downward movement of the swinging frame in the direction of the grinding wheel 43. The plate 111 has a large aperture 117 therein in which the lower end of the workpiece support 48 passes in engaging the upper surface of the grinding wheel as will clearly appear upon a consideration of Fig. 1 of the drawings.

When a surface or facet 48 has been com-

pletely ground, the screw 113 engages the stop 114 and the raising of the control plate 111 will depress the hook end 110 thereof, thus actuating the trip plate 106 to raise the spring finger 102 into the position shown in Figs. 1 and 9 in which position the finger 102 is out of engagement with the projecting lip 96 of the pawl 97. Thus, in the next movement of the roller 87 over the cam surface 88, the pawl 97 will engage the block 98 checking forward movement of the plunger 92 which will cause the swinging frame to move from the position shown in Fig. 1 to the position shown in Fig. 2.

It will thus be seen that the adjustment of screw 113 actually controls the depth or degree of cut or grinding operation performed on each section of the stone.

In the forward sliding movement of the machine or main frame, the swinging frame 31 is gradually lowered by gravity. This movement is checked to some degree by springs 118 coupled with the swinging frame, as seen at 119, and with the swinging frame, as seen at 120. This downward movement is further checked by a dashpot construction comprising cylinders 121 pivoted to the arms 28, as seen at 122, and plungers 123 having flattened sides, note Fig. 8, which operate in the cylinders 121, the plungers being pivoted, as seen at 124, to vertical columns 125 at the forward ends of the arms 28 on the swinging frame. These dashpot cushions serve to ease the engagement of the stone or workpiece in its movement into engagement with the fast rotating grinding wheel. Quite often, the surface of the stone or workpiece is sharp or irregular and this sensitive movement of the workpiece into engagement with the grinding wheel eliminates any possibility of grooving or otherwise marring the surface of the wheel. It will readily appear that as the swinging frame 31 moves upwardly, the plungers 123 are drawn upwardly in the cylinders 121 and as the frame swings downwardly, the plungers move downwardly in the bores of the cylinders and the slight flattening of the sides of the plungers 123 minimizes the escape of air to produce the cushioning or dashpot effect which is desired.

In the aforesaid swinging movement of the frame, the workpiece supporting and operating unit, in addition to being swung into the angular positions, is also actuated to rotate the holder 40, as previously described, and this operation is performed by an adjustable linkage 126 comprising telescoping parts adjustably and detachably secured, as seen at 127, the lower part being pivoted, as seen at 128, note Fig. 11, to the pin 67; whereas the upper part is pivoted to a sleeve 129 arranged upon a rod 130 of a cross-bar 131 secured to the columns 125. To each of the arms 28 are pivoted links 132, which support at their upper end a cross-bar 133, in which the columns 125 are slidably mounted. This serves to support and guide the columns in the movement of the swinging frame 31. The sleeve 129 constitutes part of or is secured to the cross-bar 133. On the cross-bar 133 is a stop 134 adapted to be engaged by an adjustable screw 135 supported in a top cross-head 136, which couples the upper ends of the columns 125. In other words, the columns 125 and crosspieces 131, 136 constitute the open work frame structure which is movable with the swinging frame and guided and reinforced by the parts 132 and 133. The screw 135 is simply employed for testing the machine and can take the place of the screw 113.

in providing a constant movement of the swinging frame from the position shown in Fig. 3 to the position shown in Fig. 4 and vice versa, each shift being accomplished upon one complete cycle of operation of the cams 23 or in one complete back and forth movement of the sliding main frame. However, when the screw 135 is in inoperative position, operation of the machine is controlled through the engagement of the workpiece with the grinding wheel.

Considering the linkage 128, it will be apparent that the sleeve 129 transmits rotary movement to the pawl 68 in rotating the workpiece holder 40 one-eighth of a revolution returning the pawl to engage the next successive tooth on a ratchet wheel 65, this last operation being assisted by a spring 137, one end of which is coupled with the pin 67 and the other end of which is secured to an arm 138 secured to the block 39.

It will appear from a consideration of Figs. 3 and 4 of the drawings that the disc 71 is larger in diameter than the conical sleeve 64; thus markings may be arranged on the disc and sleeve to indicate to the operator the position of the workpiece or the particular facets being ground when the machine is in operation. However, after the eight facets have been initially ground, the machine is allowed to continue its automatic operation for final grindings on all of the facets and when a workpiece is completely formed, the machine will continue to swing the frame and rotate the work-piece holder in each cycle of operation for the machine. This can be a clear indication to the operator that the particular workpiece in this machine has been finished and the machine is ready for the insertion of a new workpiece.

At the forward lower end of the swinging frame is arranged a large disc 139 adapted to enter a recess 140, note Fig. 1, in the table 27. The disc 139 does not seat in the base of the recess as the swinging frame is checked on its downward movement and in both positions thereof by the stop screws 116. However, should these screws be removed from the machine for any time, the disc 139 would form a support for the swinging frame.

It will be understood that the mechanism diagrammatically illustrated in Fig. 9 of the drawings is extremely sensitive in operation and by reason of this sensitive control, extreme accuracy can be produced in grinding the facets on the stone or workpiece. As a matter of fact, facets may be formed on extremely small stones or any stone which is capable of being supported in a holder 68. In this connection, it will be understood that a number of these holders will be prepared with the diamonds or other stones or workpieces set therein ready for quick insertion into the machine upon the removal of a finished workpiece. This operation is performed by simply loosening the screw 52 and swinging the arm 48 out of alignment with the holder 40 which can then be drawn upwardly through the block unit.

In the above operation, the hooked arm 61 is also swung out of engagement with the pin 50. It will be apparent that by slight alterations, substitutions and adjustments, the machine may be arranged to grind any number of facets and at different angular positions on the resulting workpiece. In this connection, it will be understood that the linkage 128 may be lengthened and shortened and the screw 50 adjusted to increase or decrease the swing of the swinging

frame. The entire machine mounted upon the base plate 15 constitutes a unit which may be supported in any desired position with respect to a grinding wheel. In some instances, a number of these units may be arranged around the peripheral of a single wheel and on the other hand, the units may be shiftable from one wheel to another.

In this connection in referring to grinding wheel, it will be apparent that the particular structure of the wheel may be modified to suit the operations to be performed on the workpiece. In some instances, it might be desirable to operate workpieces in three different stages; for example, on roughing wheels to produce rough cuts; then in a second stage, completing the cutting or grinding operation; and a third stage of polishing may also be included. It will also be understood that different weights 46 may be employed in conjunction with different workpieces and also in the use of different stones. These weights are to control the gravity pressure of the workpiece on the cutting, shaping or polishing element.

Having fully described my invention, what I claim as new and desire to secure by Letters Patent is:

1. A workpiece supporting unit for grinding machines of the character described, said unit comprising a block, a plurality of sleeves rotatably mounted in the block and relatively to each other, a workpiece supporting tool detachable with respect to said unit, a quick clamping device for retaining the tool in position in the unit, and means involving a pawl and ratchet structure rotatably mounted on the block for intermittently rotating said tool in said block.

2. A workpiece supporting unit for grinding machines of the character described, said unit comprising a block, a plurality of sleeves rotatably mounted in the block and relatively to each other, a workpiece supporting tool detachable with respect to said unit, a quick clamping device for retaining the tool in position in the unit, means involving a pawl and ratchet structure rotatably mounted on the block for intermittently rotating said tool in said block, and means retaining the tool in different positions against accidental displacement.

3. A workpiece supporting unit for grinding machines of the character described, said unit comprising a block, a plurality of sleeves rotatably mounted in the block and relatively to each other, a workpiece supporting tool detachable with respect to said unit, a quick clamping device for retaining the tool in position in the unit, means involving a pawl and ratchet structure rotatably mounted on the block for intermittently rotating said tool in said block, means retaining the tool in different positions against accidental displacement, means manually adjusting the position of the unit in the machine, and means for bodily shifting the position of the unit in the machine.

4. A workpiece supporting unit for grinding machines of the class described, a workpiece supporting tool comprising a sleeve, a workpiece gripping chuck in one end of the sleeve, means for keying the chuck against rotation in the sleeve, the inner end of the chuck being screw threaded, and a chuck actuating member engaging the threaded end of said chuck and having a milled-head projecting beyond the other end of said sleeve for clamping the workpiece in said chuck.

5. A machine for automatically moving a work-

piece relative to a grinding wheel, comprising an elongated sliding frame for moving the work-piece across the surface of the wheel, a freely swinging frame pivoted at one end to the corresponding end of the sliding frame and swingable from a position substantially paralleling the sliding frame to positions at an inclination thereto in moving the workpiece toward and from said wheel, means for actuating the sliding frame, a workpiece holder mounted in the free end portion of the swinging frame, automatically actuated means for moving the swinging frame, upon the completion of a predetermined operation on a workpiece supported in said holder, in changing the angular position of the holder in the swinging frame and with respect to said wheel, and means rotating said holder to bring another section of a workpiece in position to engage said grinding wheel.

6. A machine for automatically moving a work-piece relative to a grinding wheel, comprising an elongated sliding frame for moving the work-piece across the surface of the wheel, a freely swinging frame pivoted at one end to the corresponding end of the sliding frame and swingable from a position substantially paralleling the sliding frame to positions at an inclination thereto in moving the workpiece toward and from said wheel, means for actuating the sliding frame, a workpiece holder mounted in the free end portion of the swinging frame, automatically actuated means for moving the swinging frame, upon the completion of a predetermined operation on a workpiece supported in said holder, in changing the angular position of the holder in the swinging frame and with respect to said wheel, means rotating said holder to bring another section of a workpiece in position to engage said grinding wheel, and means for easing the movement of the workpiece into engagement with the grinding wheel.

7. A machine for automatically moving a work-piece relative to a grinding wheel, comprising an elongated sliding frame for moving the work-piece across the surface of the wheel, a freely swinging frame pivoted at one end to the corresponding end of the sliding frame and swingable from a position substantially paralleling the sliding frame to positions at an inclination thereto in moving the workpiece toward and from said wheel, means for actuating the sliding frame; a workpiece holder mounted in the free end portion of the swinging frame, automatically actuated means for moving the swinging frame, upon the completion of a predetermined operation on a workpiece supported in said holder, in changing the angular position of the holder in the swinging frame and with respect to said wheel, means rotating said holder to bring another section of a workpiece in position to engage said grinding wheel, and said automatically actuated means including adjustable means controlling the movement of the workpiece in the direction of the grinding wheel.

8. In a machine for moving a workpiece relatively to a rotating element in controlling operations performed on the workpiece by said element, an elongated reciprocating frame moving the workpiece in a predetermined path over a surface of said element, an elongated swinging frame pivoted to one end of said reciprocating frame, a workpiece supporting member detachably mounted in the free end portion of said swinging frame, and automatically actuated means, operated upon the movement of the workpiece a pre-

determined distance with respect to the surface of said element, for raising the workpiece out of engagement with said element, for rotating said member to bring a new section of the workpiece in position to engage the element and to change the angular position of said member with respect to said element preparatory to operating the new section of said workpiece over the surface of said element.

- 10 9. In a machine for moving a workpiece relatively to a rotating element in controlling operations performed on the workpiece by said element, an elongated reciprocating frame moving the workpiece in a predetermined path over a surface of said element, an elongated swinging frame pivoted to one end of said reciprocating frame, a workpiece supporting member detachably mounted in the free end portion of said swinging frame, automatically actuated means, operated upon the movement of the workpiece a predetermined distance with respect to the surface of said element, for raising the workpiece out of engagement with said element, for rotating said member to bring a new section of the workpiece in position to engage the element and to change the angular position of said member with respect to said element preparatory to operating the new section of said workpiece over the surface of said element, and means easing the movement of the workpiece into engagement with said element.

15 10. In a machine for reciprocating a workpiece back and forth over the surface of a shaping element and for moving the same toward and from said surface, a workpiece supporting member, a block in which said member is mounted, means for reciprocating the block and member back and forth over a surface of said element, means manually adjusting the block to regulate the angle of inclination of said member with respect to the surface of said element, means rotatable in said block and intermittently coupled with said member for rotating said member to bring separate sections of a workpiece in position to engage said element, and means actuated simultaneously with bringing each new section of the workpiece in position to engage said element for shifting the block in changing the angular position of said member while maintaining said adjusted angle of inclination thereof.

20 11. In a machine for automatically forming a successive series of surfaces on a workpiece, a reciprocating frame, a swinging frame pivoted at one end to the corresponding end of the reciprocating frame, a workpiece holder adjustably mounted in the free end of said swinging frame, means for actuating said reciprocating frame, means in one cycle of operation of said reciprocating frame for automatically operating the swinging frame in moving the workpiece holder into inoperative position, and means for rotating said holder and simultaneously shifting the position of the holder in the swinging frame while maintaining the adjusted position thereof preparatory to returning said swinging frame to the next series of reciprocating cycles of operation.

25 12. In a machine for automatically forming a successive series of surfaces on a workpiece, a reciprocating frame, a swinging frame pivoted at one end to the corresponding end of the reciprocating frame, a workpiece holder adjustably mounted in the free end of said swinging frame, means for actuating said reciprocating frame, means in one cycle of operation of said reciprocating frame for automatically operating the

swinging frame in moving the workpiece holder into inoperative position, means for rotating said holder and simultaneously shifting the position of the holder in the swing frame while maintaining the adjusted position thereof preparatory to returning said swinging frame to the next series of reciprocating cycles of operation, a rotatable forming element engaged by a workpiece supported in said holder in the operation of said reciprocating frame, and means on the swinging frame controlling pressure engagement of the workpiece on said element.

13. In a machine for moving a series of sections of a workpiece over the surface of a wheel in grinding and polishing said sections, a reciprocating frame, a swinging frame pivoted at one end to a corresponding end of the swinging frame, a workpiece holding unit movably supported in the other end of said swinging frame, a plunger in said swinging frame, means actuated in each reciprocating movement of said sliding frame for moving said plunger longitudinally with respect to the swinging frame and maintaining the swinging frame substantially parallel to the sliding frame, a pawl for checking movement of said plunger in controlling swinging movement of said swinging frame, and automatically actuated means controlling movement of said pawl into checking position upon completing the grinding and polishing of a section of the workpiece.

14. In a machine for moving a series of sections of a workpiece over the surface of a wheel in grinding and polishing said sections, a reciprocating frame, a swinging frame pivoted at one end to a corresponding end of the swinging frame, a workpiece holding unit movably supported in the other end of said swinging frame, a plunger in said swinging frame, means actuated in each reciprocating movement of said sliding frame for moving said plunger longitudinally with respect to the swinging frame and maintaining the swinging frame substantially parallel to the sliding frame, a pawl for checking movement of said plunger in controlling swinging movement of said swinging frame, automatically actuated means controlling movement of said pawl into checking position upon completing the grinding and polishing of a section of the workpiece, and said last named means including an adjustable stop limiting movement of the workpiece in the direction of the surface of said wheel.

15. In a machine of the class described, a workpiece holding member detachable with said unit, means for guiding said unit to move through an arcuate path, means manually adjusting the unit in supporting said member in predetermined angular position with respect to a surface over which the workpiece is operated, means for actuating said unit to reciprocate the workpiece over said surface, and means comprising a lever and a pair of pawls for automatically moving said unit in the arcuate path in intermittently changing the position of said member with respect to said surface at the termination of each series of reciprocating operations of the workpiece over said surface.

16. In a machine of the class described, a workpiece holding member detachable with said unit, means for guiding said unit to move through an arcuate path, means manually adjusting the unit in supporting said member in predetermined angular position with respect to a surface over which the workpiece is operated, means for actuating said unit to reciprocate the workpiece over said surface, means comprising a lever and a pair

of pawls for automatically moving said unit in the arcuate path in intermittently changing the position of said member with respect to said surface at the termination of each series of reciprocating operations of the workpiece over said surface, and means automatically rotating said member to move a new section of the workpiece in position to engage said surface in the arcuate movement of said unit.

17. In a machine for grinding a plurality of surfaces on a workpiece, a grinding wheel, a workpiece holder having a supporting member, means for automatically operating said holder to move the workpiece in said member toward and from the surface of said wheel, means for shifting the position of said member in said holder to bring different sections of the workpiece in position to engage said wheel, means for moving the workpiece relatively to the surface of the wheel in the grinding operation, means limiting movement of the workpiece in the direction of the surface of the grinding wheel in completing a grinding operation on one surface of a workpiece, means for adjusting the holder to a predetermined angle of inclination to the surface of the wheel, and means for automatically shifting the angular position of the holder with respect to the grinding wheel while maintaining said predetermined angle of inclination in bringing the next surface of the workpiece in position to engage said wheel.

18. In a machine for grinding a plurality of surfaces on a workpiece, a grinding wheel, a workpiece holder having a supporting member, means for automatically operating said holder to move the workpiece in said member toward and from the surface of said wheel, means for shifting the position of said member in said holder to bring different sections of the workpiece in position to engage said wheel, means for moving the workpiece relatively to the surface of the wheel in the grinding operation, means limiting movement of the workpiece in the direction of the surface of the grinding wheel in completing a grinding operation on one surface of a workpiece, said last named means being adjustable, means for adjusting the holder to a predetermined angle of inclination to the surface of the wheel, and means for automatically shifting the angular position of the holder with respect to the grinding wheel while maintaining said predetermined angle of inclination in bringing the next surface of the workpiece in position to engage said wheel.

19. A machine for moving a workpiece relatively to a rotating element in controlling operations performed on the workpiece by said element, a reciprocating frame moving the workpiece in a predetermined path over a surface of said element, a workpiece operating unit mounted on said frame, a workpiece supporting member detachable with and rotatable in said unit, means adjusting the angle of inclination of said member with respect to said surface of said element, means for automatically shifting the angular position of the unit with respect to said element while maintaining the adjusted inclination of said member, and means for automatically moving the workpiece of said member out of engagement with said element and to rotate said member in said unit to bring a new section of the workpiece in position to engage said element.

20. A machine for moving a workpiece relatively to a rotating element in controlling operations performed on the workpiece by said element, a reciprocating frame moving the work-

piece in a predetermined path over a surface of said element, a workpiece operating unit mounted on said frame, a workpiece supporting member detachable with and rotatable in said unit, means adjusting the angle of inclination of said member with respect to said surface of said element, means for automatically shifting the angular position of the unit with respect to said element while maintaining the adjusted inclination of said member, means for automatically moving the workpiece of said member out of engagement with said element and to rotate said member in said unit to bring a new section of the workpiece in position to engage said element, said unit being movable in the direction of said element in said reciprocating movement of the workpiece with respect to said element, and said last named means including adjustable means for checking movement of the unit in the direction of said element.

21. In a grinding machine, the combination with a shaping element and a member having means detachably supporting a workpiece at one end thereof, of means for automatically actuating said member in a series of operations in forming different surfaces on said workpiece, said last named means comprising means for reciprocating said member relatively to said element, means to move said member toward and from said element, means to rotate said member to bring a different surface of the workpiece therein into engagement with said element, means supporting said member at a predetermined angle of inclination with respect to the surface of said element over which the workpiece passes, and means for intermittently shifting the angular position of said member with respect to said surface of said element, while maintaining said predetermined angle of inclination of the member, in grinding the different surfaces of said workpiece.

22. In a grinding machine, the combination with a shaping element and a member having means detachably supporting a workpiece at one end thereof, of means for automatically actuating said member in a series of operations in forming different surfaces on said workpiece, said last named means comprising means for reciprocating said member relatively to said element, means to move said member toward and from said element, means to rotate said member to bring a different surface of the workpiece therein into engagement with said element, means supporting said member at a predetermined angle of inclination with respect to the surface of said element over which the workpiece passes, and means for intermittently shifting the angular position of said member with respect to said surface of said element, while maintaining said predetermined angle of inclination of the member, in grinding the different surfaces of said workpiece, and means for manually adjusting the angle of inclination of said member with respect to said surface of said element.

23. In a grinding machine, the combination with a shaping element and a member having means detachably supporting a workpiece at one end thereof, of means for automatically actuating said member in a series of operations in forming different surfaces on said workpiece, said last named means comprising means for reciprocating said member relatively to said element, means to move said member toward and from said element, means to rotate said member to

- bring a different surface of the workpiece therein into engagement with said element, means supporting said member at a predetermined angle of inclination with respect to the surface of said element over which the workpiece passes, means for intermittently shifting the angular position of said member with respect to said surface of said element, while maintaining said predetermined angle of inclination of the member, in grinding the different surfaces of said workpiece, means for slowly moving the workpiece into engagement with said surface of said element, and adjustable means for checking movement of the work piece in the direction of said surface.
- 10 24. In a machine for grinding and polishing a predetermined number of facets on a precious stone, the combination with a grinding and polishing wheel, of means for reciprocating a stone over a surface of said wheel a number of times in grinding each facet, automatically actuated means for moving the stone out of engagement with the wheel upon the formation of a facet on one section of the stone and then moving another section of the stone into engagement with said wheel, said last named means comprising a member supported at predetermined inclination to the surface of said wheel, and means for shifting said member to different angular positions with respect to said wheel surface while maintaining said inclination of said member.
- 20 25. In a machine for grinding and polishing a predetermined number of facets on a precious stone, the combination with a grinding and polishing wheel, of means for reciprocating a stone over a surface of said wheel a number of times in grinding each facet, automatically actuated means for moving the stone out of engagement with the wheel upon the formation of a facet on one section of the stone and then moving another section of the stone into engagement with said wheel, said last named means comprising a member supported at predetermined inclination to the surface of said wheel, means for shifting said member to different angular positions with respect to said wheel surface while maintaining said inclination of said member, said second named means including an adjustable stop limiting movement of the stone in the direction of said wheel surface, and means for manually adjusting the angle of inclination of said member with respect to the surface of said wheel.
- 30 26. In a machine of the class described, the combination with a shaping element, of a workpiece mechanism for moving a workpiece supported therein toward and from, and back and forth over the surface of said shaping element, said mechanism comprising a workpiece supporting member having a predetermined angle of inclination to the surface of said shaping element, means for rotating the member in bringing different sections of the workpiece therein in position to engage said element, means shifting the angular position of said member to the element while maintaining said predetermined angle of inclination, means imparting back and forth reciprocating movement to said mechanism, and adjustable means checking movement of the mechanism in the direction of said element in controlling operation of the shaping element upon the respective sections of the workpiece in the several back and forth reciprocating movements of the respective sections of the workpiece over said element.
